UNITED STATES PATENT OFFICE

2,529,828

HOT-AIR GAS HEATER WITH RADIANT

George William Zimbelman, Signal Mountain, Tenn., assignor to Samuel Stamping and Enameling Company, Chattanooga, Tenn., a corporation of Tennessee

Application March 13, 1946, Serial No. 653,977

2 Claims. (Cl. 126—90)

1

This invention relates to gas heaters.

The invention is more particularly concerned with the back wall of gas heaters before which are positioned clay radiants.

Back walls for gas heaters have usually been constructed of clay, although some have been constructed of steel.

While the clay back walls heretofore used were satisfactory, they nevertheless offered some disadvantages, particularly in that they were highly heat absorbing and in time cracked as a result thereof. Furthermore, such clay back walls were easily broken under impact with the result that their efficiency was more or less impaired.

Steel back walls as heretofore constructed overcame certain disadvantages of the clay back wall, particularly in that they were not easily broken.

Such steel back walls are, however, subject to warping and transmit a high percentage of heat to the rear thereof rather than providing for passage of the heat into a room to be heated.

A primary object of the present invention is the provision of a sheet steel back wall which is ribbed to prevent warping thereof.

A further object of the invention is the provision of a sheet steel back wall mounted within a casing or shell with provision for a circulation of cool air upwardly along the back wall.

A still further object of the invention is the provision of a porcelain finished sheet steel back wall which is substantially lighter in weight, in some instances as much as 50 percent, far cheaper, economical and simple to manufacture and more durable than the clay back walls now in use.

With the above objects in view, together with others that may present themselves in the course of the following disclosure, reference will now be had to the accompanying drawings illustrating a preferred embodiment of the invention.

In the drawings:

Fig. 1 is a front elevational view of a cabinet gas burner showing the application of the invention thereto and with the radiants omitted.

Fig. 2 is a back elevational view with the lower portion broken away.

Fig. 3 is a horizontal sectional view on an enlarged scale as observed in the plane of line 3—3, Fig. 1.

Fig. 4 is a vertical sectional view as observed in the plane of line 4—4, Fig. 2.

Fig. 5 is a view similar to Fig. 4 on a larger

scale and showing one of the radiants in section and its operative relation to the back wall.

In the drawing H designates the heater which includes a burner compartment 10 and a back wall supporting shell 11.

In heaters of this character, a back wall is mounted in the shell forming a support for the clay radiants such as indicated at R in Fig. 5.

The improved back wall of the instant invention is a rectangular sheet steel plate 12 which, as indicated in Figs. 4 and 5, is disposed substantially intermediate the front and back of the shell but slopes slightly upwardly and forwardly.

The plate 12 is constructed of relatively light gauge sheet steel and is provided with pressed ribs 13 having their convex surfaces disposed forwardly as shown. The plate is porcelain finished for providing greater heat radiation therefrom.

The plate 12 is preferably provided with side flanges 14 secured as at 15 to the sides 16 of the shell 11.

An angular sheet steel strip 16' is preferably utilized to support the lower edge of the plate 12.

A sheet steel strip 17 is suitably secured to the upper edge of the plate and projects horizontally forward to the upper front wall 18 of the shell 11 and which wall depends from a top wall 18', thereby sealing off a chamber in the shell to the rear and top of the plate.

The rear wall 19 of the shell is provided with a horizontal row of relatively large apertures 20 adjacent the lower edge thereof for admission of cool air into the shell to the rear of the plate 12. The upper front wall of the shell is provided

with a row of apertures 21, and the strip 17 is provided with a row of relatively small apertures 22 which are disposed substantially within the space defined between wall 12 and the radiants R which abut the ribs as is more clearly indicated in Fig. 5.

As indicated in Figs. 4 and 5, cool air close to the floor will enter apertures 20 as is indicated by the arrow c. This air will move upwardly rearwardly of and along the back of plate 12 thereby exerting a cooling action thereon which eliminates fire hazards.

This cool air will, however, absorb a high percentage of heat as it moves upwardly as indicated by the arrow w and the warmed air will travel horizontally through the apertures 21 into the room being heated. The hot air between the ribs as well as between plate 12 and the radiants R will pass upwardly and out through apertures 22 as indicated by the arrow h in Fig. 5.

With this improved construction the heated

air will move horizontally close to the floor rather than being radiated toward the ceiling, which has been highly objectionable in prior forms of heaters.

The ribs 13 function to reinforce the plate 12 to prevent warping in use and they further provide a space between the plate and the radiant which is effectively ventilated by apertures 22.

The improved back wall 12 is non-breakable, non-warpage, and is approximately only 50% of the weight of clay back walls heretofore used.

By mounting the improved back wall in a shell as disclosed it is prevented from becoming dangerously hot by means of the cooling air entering the apertures 20, and this air which absorbs heat from the plate moves horizontally with the heated air emerging from apertures 22 at the front of the plate and thence through the apertures 21 and into the room being heated.

While I have disclosed the invention in accordance with the single specific embodiment thereof, such is to be considered as illustrative only and not restrictive, the scope of the invention being defined in the subjoined claims.

What I claim and desire to secure by U. S. Letters Patent is:

1. In a gas heater, a shell including a vertical rear wall, opposite vertical side walls, a top wall interconnecting the upper edges of the rear and side walls, a front wall depending from the front edge of the top wall, the lower edge of the front wall defining the upper edge of a front opening in the shell, and a horizontal wall disposed below the top wall and extending rearwardly from the front wall and terminating between same and the rear wall, a sheet steel back wall mounted between the side walls and beneath the horizontal wall in spaced relation to the rear wall and providing with said shell walls a chamber, the back wall having spaced parallel ribs defining upright channels in the rear face of the back wall and providing supports for clay radiants set into the shell and also defining vertical air spaces between the back wall and the radiants, apertures in the rear wall adjacent the bottom thereof, apertures in the front wall above the horizontal wall, and apertures in the horizontal wall above the air spaces between the back wall and the radiants, the apertures in the rear and front walls providing for the flow of cool air upwardly along the rear face of the back wall, and the apertures in the horizontal wall providing for the flow of air

upwardly between the back wall and radiants and which air becomes heated from contact with the wall and radiants and passes horizontally with the air admitted through the apertures in the rear wall, through the apertures in the front wall.

2. In a gas heater, a shell including a vertically disposed rear wall, vertically disposed side walls, a top wall, and a front wall depending from the top wall and terminating a short distance from the top of the shell, a sheet steel back wall disposed within the shell intermediate the rear and front walls and extending from one side wall to the other and having its lower edge substantially aligned with the lower edges of the rear and side walls, the back wall being slightly inclined to the vertical in the direction of the front wall and having its upper edge horizontally spaced from the front wall adjacent the lower edge thereof, a sheet steel strip having one edge thereof secured to the upper edge of the back wall and extending horizontally therefrom with its opposite edge contacting the front wall, air admission apertures in the lower portion of the rear wall, air exit apertures in the front wall above said horizontal strip, said back wall being provided with spaced parallel ribs extending from the bottom to the top edges thereof, the ribs being pressed from the wall and providing channels in the rear face thereof and spaced supports at the front face thereof for supporting clay radiants in spaced relation to the wall, and apertures in the horizontal strip above the spaces between the supports.

GEORGE WILLIAM ZIMBELMAN.
